[57] CLAIM

The ornamental design for an unvented gas log set, as shown and described.

DESCRIPTION

FIG. 1 is a perspective view of an unvented gas log set showing my new design;

FIG. 2 is a front view thereof;

FIG. 3 is a rear view thereof;

FIG. 4 is a right end view thereof;

FIG. 5 is a left end view thereof;

FIG. 6 is a top view thereof; and,

FIG. 7 is a bottom view thereof.

The broken line showing of logs in FIG. 1 is for illustrative purposes only and forms no part of the claimed design.
